UNITED STATES PATENT OFFICE.

HENRY W. GONIA, OF BERWIND, WEST VIRGINIA.

TROLLEY-HANGER.

1,098,250.

Specification of Letters Patent. Patented May 26, 1914

Application filed October 25, 1913. Serial No. 797,250.

To all whom it may concern:

Be it known that I, HENRY W. GONIA, a citizen of the United States, residing at Berwind, in the county of McDowell and State of West Virginia, have invented certain new and useful Improvements in Trolley-Hangers, of which the following is a specification.

This invention relates to improvements in suspension devices for wires, and particularly to those known as trolley hangers adapted especially for use in mines where it is necessary to provide a special support owing to the disposition of the same in rock, coal or similar hard material of the ceiling of said mine.

The advantages and objects of the invention will be more clearly understood when it is mentioned that it is customary to drill a hole in the mine ceiling in which the trolley hanger is inserted and on account of the nature of the material of the ceiling the difficulty of supporting the hanger so that it will not become loose in use and yet be capable 25 of removal when desired, has been very great.

The main object of my invention, therefore, has been to provide a hanger which will be effectually insulated from the conductor 30 by an insulating member, the attachment of which member to the hanger supporting member will operate to positively engage the supporting member with the mine ceiling.

Another object in view is to provide a construction which will be simple and so arranged that the parts subject to breakage may be easily and quickly replaced without the necessity of discarding the whole hanger.

With the above and other objects in view, this invention consists in the construction, combination and arrangement of parts all as hereinafter more fully described, claimed and illustrated in the accompanying 45 drawings, wherein:

Figure 1 is a side elevation of a hanger constructed in accordance with my invention. Fig. 2 is a sectional view showing the details of construction of the same; and Fig. 3 is a 50 detail view of the wire engaging member or clamp employed in my device.

Throughout the following detail description, and on the several figures of the drawings, similar parts are referred to by like 55 reference characters.

Referring to the drawings by numerals, 1 represents the mine ceiling which as heretofore mentioned generally comprises hard substances and the numeral 2 illustrates an opening drilled in the ceiling. Into the opening is adapted to be inserted the supporting member 3 for my trolley hanger which supporting member has mounted in a transverse groove at its upper extremity a pair of opposing dogs 4, said dogs being disposed upon the common pivot pin 5 passing through the supporting member 3. Mounted upon the supporting member for longitudinal movement thereof is disposed a sleeve 6 which is provided at opposite sides 70 with slots 7, said slots terminating at their lower extremities in beveled or cam surfaces 7' adapted to coöperate with the dogs 4 for operation thereof in a manner to be hereinafter more fully set forth.

The lower end of the supporting member 3 is threaded as indicated at 3', and upon this extremity is screwed the insulating member for the trolley hanger comprising the shell 8 of bell shape form having on its upper surface a boss 8' provided with a threaded opening 8'' whereby the shell and its coöoperating parts may be connected with the supporting member 3. Within the bell shaped shell 8 is disposed a removable insulating member 9 of suitable non-conducting material such as fiber or the like, and said member 9 is formed with a central concave recess to accommodate the head of a bolt 10 which forms the support for the wire engaging member or clamp 11. The bolt 10 is secured in a position coöoperating with the insulating member by means of the nut 12 having a central opening 12' through which the bolt 10 passes and said nut at its upper peripheral portion is threaded for connecting the same to the internally threaded portion of the shell 8. To effectively insulate the bolt 10 from the shell and the hanger support it is preferably desired that the nut 12 shall be provided with an internal recess 12' in which is disposed an insulating washer or washers 13 surrounding the upper portion of said bolt. Coöoperating with the washers 13 is an insulating sleeve 14 passing through the washers 13 and extending along the bolt to a point preferably exterior to the nut 12. The bolt 10 has threaded connection with the upper end of the wire engaging member 110

11 and between said member and nut is interposed a further insulating member or washer 15.

As shown clearly in Figs. 2 and 3 the wire engaging member 11 comprises the body portion 11' having threaded connection with the bolt 10 and formed at one side and extending downwardly is an integral clamping member 11^a. Coöoperating with the clamping member 11^a is a corresponding clamping member 11^b, pivotally secured to the body portion 11' on the pivot 11^c. The clamping members 11^a and 11^b are formed with openings therethrough in which is disposed a clamping bolt 11^d and when the wire 16, of the usual type, is disposed between the clamping members, this bolt 11^d is suitably tightened so as to positively hold the wire in supported condition.

In actual use the operation of the invention will be clear from the drawing, though it may be stated that when the opening 2 has been provided in the ceiling of the mine, the hanger support 3 with its dogs 4 in retracted position and with the sleeve 6 movable thereon is inserted in said opening, which may be of the exact size of the exterior of said sleeve. When the support is at its proper position within the opening, the shell 8 of the insulating member is screwed on to the lower threaded extremity of the member 3, the boss 8' contacting with the sleeve 6 and causing the same to move longitudinally of the supporting member. Such movement of the sleeve brings the cam portion 7 of the sleeve 6 into contact beneath the dogs 4 operating said dogs to project them laterally into the walls of the opening. It will be evident that as weight is placed upon the hanger, the tendency of the dogs is to further embed themselves in the walls of the opening 2 and the amount of this projection of the dogs depends upon the weight and the distance the shell 8 is screwed upon the supporting member 3. It will be also noted from Fig. 2 of the drawing that the supporting member at its head portion is somewhat enlarged and the upper or corresponding interior portion of the sleeve 6 is enlarged so as to prevent the extension of the dogs 4 into too great an angular position, this being desirable since it is found necessary at times to remove the hanger supports.

The removal of the trolley hanger comprehended by my invention is very easily accomplished by the removal of the insulating member from the supporting member 3, and tapping said supporting member on its extremity projecting beneath sleeve 6, which will cause the dogs to move inwardly to their original retracted position until they are flush with the sides of said sleeve. Withdrawal of the sleeve and its coöperat-

ing supporting member may easily be accomplished when this has been carried out.

As has been heretofore mentioned, devices of this character are subject to breakage and when in the usual types of trolley hangers the insulating member is formed with insulating material pressed thereinto the whole hanger becomes useless upon the breakage of any of its parts. With my construction, however, the insulating material is so disposed as to be removable at all times by the unscrewing of the nut 12 from the shell 8 permitting the bolt 10 to be withdrawn and access to the main insulating member 9 had. The provision of an adjustable wire engaging clamp is also conducive to ready installation or disposition of the wire of the electric conductor 16 which may be loosely inserted between the clamping members 11^a and 11^b and when drawn tightly into proper tension, said clamping members may be tightly clamped about said wire.

Having thus described my invention, what I claim as new is:

1. A trolley hanger comprising a sleeve adapted to be inserted into an opening, a supporting member disposed within the sleeve and movable outwardly of the opening and the sleeve, wall engaging means connected to the inner supporting member aforesaid, housed by said sleeve and movable through said sleeve in upward opposite directions upon movement of the supporting member in the outward direction aforesaid, and means connected to the supporting member for causing said outward movement.

2. A trolley hanger comprising a sleeve adapted to be inserted in an opening, a supporting member disposed within the sleeve, wall engaging dogs connected to the inner supporting member aforesaid and adapted to be extended out of the sleeve upon outward movement of the supporting member therefrom and to be withdrawn into the sleeve upon relative movement of said supporting member inwardly of the sleeve, and a common pivot for said dogs.

3. In a trolley hanger, a supporting member, wall engaging members carried by said supporting member, a sleeve disposed about and movable longitudinally of said supporting member and adapted to coöperate with the wall engaging members of the supporting member, and means connected to the supporting member and adapted to coöperate with said sleeve for actuating the wall engaging members to project the latter beyond said sleeve, said wall engaging members being arranged for retraction into said sleeve upon longitudinal movement of the supporting member.

4. In a trolley hanger, a supporting member, opposing dogs pivotally mounted at one

end of said supporting member, a sleeve disposed about said supporting member and having opposing slots therein terminating in cam surfaces adapted for coöperation with the dogs aforesaid, and means removably connected to the supporting member and contacting with the sleeve for movement of the same longitudinally of the supporting member to project the dogs therefrom.

5. In a trolley hanger, a supporting member, opposing dogs pivotally mounted at one end of said supporting member, a sleeve disposed about said supporting member and having opposing slots therein terminating in cam surfaces adapted for coöperation with the dogs aforesaid, and means removably connected to the supporting member and contacting with the sleeve for movement of the same longitudinally of the supporting member to project the dogs therefrom, said supporting member being enlarged at one end and the opening of the sleeve aforesaid being correspondingly enlarged whereby to limit movement of the sleeve with respect to the supporting member.

6. In a trolley hanger, a supporting member, independent opposing dogs pivotally connected to the supporting member for

movement outwardly and upwardly into engaging position, wire engaging means, a 30 member intermediate the wire engaging means and the supporting member, and means coöoperating with the intermediate member to actuate the dogs for extension of the same laterally from the supporting member. 35

7. A trolley hanger comprising a supporting member, wall engaging means pivotally carried by said supporting member and movable outwardly and upwardly into engaging 40 position, a sleeve for actuating the wall engaging means, wire engaging means supported by said supporting member, and a rotatable connecting member detachably connecting the wire engaging means with 45 the supporting member and adapted to co-operate with the sleeve to actuate the wall engaging means upon rotation of the connecting member.

In testimony whereof I affix my signature 50 in presence of two witnesses.

HENRY W. GONIA.
